UNITED STATES PATENT OFFICE.

BENJAMIN LA PISH, OF NORWOOD, PENNSYLVANIA, ASSIGNOR TO THE BELBER TRUNK & BAG COMPANY, OF PHILADELPHIA, PENNSYLVANIA, A CORPORATION OF PENNSYLVANIA.

LABEL HOLDER.

Application filed December 26, 1922. Serial No. 608,888.

To all whom it may concern:

Be it known that I, BENJAMIN LA PISH, a citizen of the United States, and a resident of Norwood, in the county of Delaware and State of Pennsylvania, have invented an Improvement in Label Holders, of which the following is a specification.

My invention relates to devices which are adapted to be attached to trunks and other shipping receptacles for holding labels on which may appear the address of the consignee or other information as may be desired.

The general object of the invention is to provide an improved but simple construction of device of the character indicated comprising means whereby a label or labels containing the information desired to be imparted may be readily inserted in place therein and thereafter securely retained in place in such manner that it or they are not liable to be accidentally removed from the holder during the transit of the receptacle to which it is secured.

A further object of the invention is to provide a holder having novel means for engaging and retaining in place the labels which are inserted therein.

To these and other ends my invention comprehends the construction as hereinafter described in detail and as illustrated in the accompanying drawing which forms a part of this application and in which I have illustrated one form of mechanical embodiment thereof. It will be understood, however, that changes in the details of construction may be made within the scope of the claims without departing from the invention.

In the drawing:

Fig. 1 is a top plan view of a label holding device embodying my invention and also showing a portion of the receptacle to which it is attached;

Fig. 2 is a longitudinal sectional view taken on the line 2—2 of Fig. 1;

Fig. 3 is a bottom plan view of the device removed from the receptacle; and

Fig. 4 is a transverse sectional view taken on the line 4—4 of Fig. 1.

Referring to the drawing: 1 designates a plate of suitable metal which, in the construction shown, is of rectangular shape and 2 designates a portion of a receptacle, such as a trunk, to which it is secured by means

of rivets 3. Other suitable fastening means may be employed if desired. The plate 1 is provided with slots 4 which extend longitudinally thereof, the side walls of which are beveled inwardly as indicated at 5. 60 Situated adjacent one end of each of these slots is a slot 6 which extends transversely of the plate 1 and at right angles to the lengths of said slots. This slot 6 is separated from the slots 4 by the narrow portions 7 of the plate 1. The under side of the plate 1 is provided with grooves 8 situated adjacent the opposite sides of the slots 4 and a groove 9 situated adjacent the left hand ends thereof. The outer edges of 70 these grooves terminate in shoulders 10 as indicated. The under side of the said plate 1 is also provided with a groove 11 adjacent the outer edge of the slot 6, which groove likewise terminates in a shoulder as indicated. The presence of the grooves 8 provides the elongated projection or ridge-like portions 15 upon the under side of the plate intermediate or between the slots 4. The under sides of the portions 7 in alinement 80 with the slots 4 are cut away so as to provide depressions or slots therein for the strips 16 of paper, paste-board or the like which are inserted through the slot 6 to positions underneath the plate 1 at the bottoms of the slots 4. The opposite edges of 85 these strips are situated within the grooves 8 while the opposite ends thereof are situated within the grooves 9 and 11, the latter being the groove upon the under side of the plate 1 adjacent the outer edge of the slot 6. The ends of the elongated projections 15 which terminate at the inner edge of the slot 6 are tapered, as indicated at 17, so as to facilitate the insertion of the strips 95 16 into position within or at the bottoms of the slots 4. The strips having been inserted into position within or at the bottoms of these slots the outer ends thereof are inserted into the groove 11, as indicated 100 in Fig. 1, so that the overhanging outer edge portion of the slot 6 overlies the said ends and operates to retain the strips 16 in position. The outer ends of the said strips may be lifted so as to disengage the same 105 from underneath the adjacent overlying outer edge portion of the slot 6, after which the said strips may be readily removed by pulling the same outwardly.

The strips are provided primarily for the 110

address of the consignee of a shipped package or receptacle, but it will be understood that any other information desired may be placed upon the said strips.

5. In the construction as illustrated it will be noted that I have provided a plurality of slots for receiving a plurality of strips each of which may contain a single item of information, but it will be understood that 10 the invention is not limited to any particular number of slots and that the number may be increased or diminished as may be desired. One of the important and essential features of my invention is the provision of 15 means for facilitating the insertion of strips into position within the holder and of means for retaining and holding said strips securely in place after they have been inserted and positioned.
20. It will be seen that by my invention I have provided a label holding device of simple construction which when attached to a trunk or other shipping receptacle provides convenient, practical and efficient 25 means for receiving and holding a label on which may appear such information as it is desired to impart, such as the address of the consignee, or it may be arranged to contain the return address of the shipper.
30. Having thus described my invention, what I claim and desire to secure by Letters Patent is:
35. 1. A label holder consisting of a plate having one or more slots therein adapted for the reception of a label or labels and having means for supporting a label or labels in rear of said slot or slots and having a slot extending substantially at right angles to said first named slot or slots and 40. spaced therefrom, and said plate also having a cut-out portion upon its under side adjacent the upper edge of said second named slot forming an overhanging lip under which an end or ends of said label or

labels projects or project, substantially as 45 described.

2. A label holder consisting of a plate of suitable metal having a plurality of slots therein, which plate is provided with grooves upon its under side adjacent the 50 opposite side edges of said slots and adjacent one end thereof, and the said plate being also provided with a slot situated a distance from the opposite ends of the said slots and extending at right angles thereto, and the under side of said plate being also provided with a groove adjacent the outer edge of the said transversely extending slot, and portions of the under side of the said plate intermediate the said transversely extending slot and the adjacent ends of the first named slots being removed, substantially as and for the purpose described.

3. In a label holder, the combination of a plate of suitable metal which is adapted to be secured to a shipping receptacle, which plate is provided with a plurality of slots arranged in parallel relation to each other, and a slot extending transversely of the first named slots and spaced therefrom, the 70 under side of which plate is provided with grooves adjacent the opposite sides of the first named slots and one end thereof opposite the end adjacent the second named slot and also with a groove adjacent the outer edge of the said second named transversely extending slot, means for securing the said plate to a receptacle, and labels within the said first named slots the opposite edges of which are seated in the grooves adjacent the 75 edges and ends thereof, and one end of each of said labels being situated in the groove adjacent the outer edge of the second named transversely extending slot.

In testimony that I claim the foregoing as my invention, I have hereunto signed my name this 6th day of December, A. D. 1922.

BENJAMIN LA PISH.
